UNITED STATES PATENT OFFICE.

ANDREW P. HAWN, OF LAPORTE, INDIANA, ASSIGNOR, BY DIRECT AND MESNE ASSIGNMENTS, TO JOHN WOLF, OF LAPORTE, INDIANA.

STOP MECHANISM.

1,192,779.

Specification of Letters Patent. Patented July 25, 1916.

Original application filed September 23, 1912, Serial No. 721,746. Divided and this application filed February 27, 1913. Serial No. 750,946.

To all whom it may concern:

Be it known that I, ANDREW P. HAWN, a citizen of the United States, residing at Laporte, in the county of Laporte and State 5 of Indiana, have invented a certain new and useful Improvement in Stop Mechanisms, of which the following is a specification, the subject-matter of this application being subject-matter divided out of my copending application, Serial No. 721,746, filed September 10 23, 1912.

My invention relates to improvements in locking and stopping mechanism such as is particularly adapted for instance to use in 15 connection with plow lift devices although it is evident such mechanism may be used in a large number of situations where it is desirable to draw in on the cable by means of a rotating member and to lock the cable when 20 drawn in.

It is illustrated diagrammatically in one form in the accompanying drawing, wherein—

Figure 1 is a detail side elevation with 25 parts in section; Fig. 2, a front elevation with parts broken away; Fig. 3, a detail side elevation of the latch.

Like parts are indicated by like letters throughout the several figures.

30 The supporting frame A has projecting upwardly therefrom the bracket arm A¹ in which is rotatably mounted the shaft A² driven from any suitable source of power not shown. The ratchet wheel A³ is pinned 35 on the shaft A² and rotates with it. The pulley or sheave A⁴ is rotatably mounted upon the shaft A². The collar A⁵ is pinned to the shaft A² adjacent the sheave A⁴ and holds it in position against lateral displacement. The cable A⁶ is anchored in the sheave A⁴ at A⁷ and is adapted to pass 40 around the sheave indicated in Fig. 1 over the sheave A⁸ and lead to the object to be actuated or controlled which I have indicated by a lever A⁹ in adjustable connection by means of the screw A¹⁰ and nuts A¹¹. The sheave A⁴ has pivoted thereon the latch or a cam lever B perforated at B¹ to surround the shaft A² the perforation B¹ being 45 of sufficient size to permit the latch to oscillate without interference from the shaft. The finger B² projects outwardly from the latch beyond the periphery of the sheave A⁴.

The dog B³ is pivoted on the sheave A⁴ and is provided with the ratchet-engaging hook 55 or ratchet lever B⁶ at one end yieldingly pressed toward the ratchet A³ by the spring B⁶ provided at the other end with the pin B⁷ in engagement with the cam slot B⁸ in the latch B. The sheave A⁴ is provided in 60 its periphery at a point substantially diametrically opposed to the pivotal point of the latch with the teeth or notches B⁹ B¹⁰ in opposition to and adapted to be engaged by a block B¹¹ on the lever C. The lever C 65 is rotatably mounted on the frame A being yieldingly drawn toward the sheave A⁴ by the spring C¹ pressing against the washer C² adjustably mounted on the bolt C³. This bolt is mounted in the lever. The guide 70 bar C⁴ is slidably mounted on the lever C being guided therealong by the clips C⁵, is yieldingly held in the lower position by the spring C⁶ and provided with the finger C⁷ projecting into the path of the finger B². 75 The shaft D is rotatably mounted in the arm A¹ and carries the cam D¹ rigid thereon in opposition to the tappet D² which is adjustably mounted in the lever C so that the rotation of the shaft D will cause the cam 80 D¹ to press the lever C backward. The cable D³ is also provided whereby the lever may be directly operated.

It will be evident that, while I have shown in my drawing an operative device, still 85 many changes might be made in size, shape and arrangement of parts without departing materially from the spirit of my invention, and I wish therefore that my drawing be regarded as in a sense diagrammatic. 90

The use and operation of my invention is as follows: Assuming the device to be in the position shown with the cable wound up and the part A⁹ in the retracted position it becomes desirable to release the parts 95 to permit the cable to be withdrawn from the sheave thus freeing the part A⁹. This may be done by a timing device not shown which rotates the shaft D so that the cam thereon presses the tappet and forces the 100 lever away or it may be done by pulling on the cable D³ to draw the lever out. In any event the rotation of the lever about its pivotal point away from the sheave will tend to free the block on the lever from 105 its engagement with the tooth or notch

B¹⁰ in the sheave when the parts are in the position shown and the sheave will then rotate making one revolution. The block B¹¹ engages the notch or tooth B⁹ to hold the sheave against further rotation. Meanwhile, the finger B² which projects from the latch B will have been brought around to a position beneath the finger C⁷ on the rod C⁴ but the dog B³ will still be held out of engagement in the ratchet A³ owing to the relative positions of the latch and dog. When the member A⁹ is to be retracted to lift a plow or perform any other work it is only necessary to withdraw the lever C. 15 This will then permit the sheave A⁴ to rotate a little farther in response to the tension in the cable A⁶ thus causing the finger C⁷ to exert a downward pressure on the finger B² to rotate the latch in a clockwise direction with respect to the sheave A⁴. This will bring the roller B⁷ into the outermost portion of the cam slot B⁸ and permit the dog B⁵ to be drawn by the spring B⁶ into engagement with the ratchet teeth. 20 Since the shaft A² is at all times rotating being driven by any suitable source of power not shown this will make a connection between the sheave and the power source. The rotation of the shaft will cause the sheave 25 to rotate in a clockwise direction until the gear or notch B¹⁰ again comes into line with the block B¹¹ on the lever C and the block will then be forced into the notch and hold the sheave. Meanwhile, however, at about 30 the same time the finger B² will have been brought into contact with the finger C⁷ and will be rotated with respect to the sheave in a counter-clockwise direction thus forcing the roller B⁷ into the innermost end of the 35 cam slot and drawing the dog out of connection with the ratchet, thus freeing the sheave which is now returned to the position of Fig. 1. This cycle of events can be produced as often as need be. Each withdrawal of the lever will operate the device 40 either to pay out or draw in the cable as the case may be.

I claim:

1. The combination with a shaft, and 50 a ratchet wheel rigidly mounted thereon, a disk mounted for rotation thereabout, a ratchet lever pivoted on the disk for engagement with the ratchet wheel, a cam lever pivoted on the disk and means for rocking it to operate the ratchet lever.

2. The combination with a shaft and 55 a ratchet wheel rigidly mounted thereon, a disk mounted for rotation thereabout, a ratchet lever pivoted on the disk for engagement with the ratchet wheel, a cam lever pivoted on the disk and means responsive to the rotation of the disk for rocking it to operate the ratchet lever.

3. The combination with a shaft and 60 a ratchet wheel rigidly mounted thereon, a

disk mounted for rotation thereabout, a ratchet lever pivoted on the disk for engagement with the ratchet wheel, a cam lever pivoted on the disk and means for rocking it to operate the ratchet lever, said means 70 comprising a yielding stop and a finger projecting from the cam lever into the path of said stop.

4. The combination with a shaft and 75 a ratchet wheel rigidly mounted thereon, a disk mounted for rotation thereabout, a ratchet lever pivoted on the disk for engagement with the ratchet wheel, a cam lever pivoted on the disk and means responsive to the rotation of the disk for rocking it to operate the ratchet lever, said means comprising a yielding stop and a finger projecting from the cam lever into the path of said stop. 80

5. The combination with a shaft and 85 a ratchet wheel rigidly mounted thereon, a disk mounted for rotation thereabout, a ratchet lever pivoted on the disk for engagement with the ratchet wheel, a cam lever pivoted on the disk and means for rocking 90 it to operate the ratchet lever, said means comprising a yielding stop and a finger projecting from the cam lever into the path of said stop, a lever upon which said stop is mounted said disk being notched, a stop on 95 said lever adapted to yieldingly engage the notches on the disk.

6. The combination with a shaft and 100 a ratchet wheel rigidly mounted thereon, a disk mounted for rotation thereabout, a ratchet lever pivoted on the disk for engagement with the ratchet wheel, a cam lever pivoted on the disk and means responsive to the rotation of the disk for rocking it to operate the ratchet lever, said means comprising 105 a yielding stop and a finger projecting from the cam lever into the path of said stop, a lever upon which said stop is mounted said disk being notched, a stop on said lever adapted to yieldingly engage the notches on 110 the disk.

7. In a combination a rotating shaft, a ratchet wheel rigidly mounted thereon, a disk mounted for rotation thereabout, a ratchet lever pivoted upon the disk, yielding 115 means for drawing the ratchet engaging end of said lever toward the ratchet wheel, a cam lever mounted on the disk in engagement with one end of said ratchet lever.

8. In a combination a rotating shaft, a 120 ratchet wheel rigidly mounted thereon, a disk mounted for rotation thereabout, a ratchet lever pivoted upon the disk, yielding means for drawing the ratchet engaging end of said lever toward the ratchet wheel, a cam 125 lever mounted on the disk in engagement with one end of said ratchet lever, a finger projecting from said cam lever beyond the periphery of the disk and a control lever adjacent the disk. 130

9. In a combination a rotating shaft, a ratchet wheel rigidly mounted thereon, a notched disk mounted for rotation thereabout, a ratchet lever pivoted upon the disk, 5 yielding means for drawing the ratchet engaging end of said lever toward the ratchet wheel, a cam lever mounted on the disk in engagement with one end of said ratchet lever, a finger projecting from said cam lever 10 beyond the periphery of the disk, a control lever adjacent the disk and a yielding stop on the control lever in the path of the finger.

10. In a combination a rotating shaft, a ratchet wheel rigidly mounted thereon, a notched disk mounted for rotation thereabout, a ratchet lever pivoted upon the disk, 15 yielding means for drawing the ratchet engaging end of said lever toward the ratchet wheel, a cam lever mounted on the disk in engagement with one end of said ratchet lever, a finger projecting from said cam lever beyond the periphery of the disk, a control 20 lever in the path of the finger, a stop on the control lever adapted to engage the notches in the disk and yielding means for drawing 25 the control lever toward the disk into operative relation therewith.

and a stop on the control lever adapted to engage the notches in the disk.

11. In a combination a rotating shaft, a ratchet wheel rigidly mounted thereon, a notched disk mounted for rotation thereabout, a ratchet lever pivoted upon the disk, 30 yielding means for drawing the ratchet engaging end of said lever toward the ratchet wheel, a cam lever mounted on the disk in engagement with one end of said ratchet lever, a finger projecting from said cam lever beyond the periphery of the disk, a control 35 lever in the path of the finger, a stop on the control lever adapted to engage the notches in the disk and yielding means for drawing 40 the control lever toward the disk into operative relation therewith.

In testimony whereof, I affix my signature in the presence of two witnesses this 20th day of February, 1913.

ANDREW P. HAWN.
